PRESSING MACHINE AND CONTROL
MECHANISMJoseph P. Daly, New York, N. Y., assignor to The
American Laundry Machinery Company, Nor-
wood, Ohio, a corporation of Ohio

Application October 6, 1934, Serial No. 747,173

22 Claims. (Cl. 38—41)

This invention relates to pressing machines such as are used for laundry or garment pressing work. The invention has relation both to the operating means and mechanism for producing 5 relative motion of the pressing members and to the control means for the power mechanism used for operating the press.

The invention has more particular relation to that type of press in which the pressing members 10 are relatively movable toward and from each other both to preliminarily close them upon the work and to produce final or heavy pressure for the pressing operation, either or both of the preliminary closing and final pressure movements 15 being produced by power means, and more particularly to such a press in which the power transmitting mechanism for operating the pressing members includes separable parts adapted to be coupled or uncoupled, and which transmit the 20 power effect of the motor to the pressing members only when they are coupled.

One object of the invention is to provide a press of this kind which includes two hand control means which compels the operator to keep 25 both of his hands busy in order to bring the parts to that position in which the pressing members are preliminarily closed and the separable parts are coupled to establish power transmitting relation between the motor means and the pressing 30 members in order to instigate the final pressure effect, thus safeguarding the operator against injury.

Another object of the invention is to provide a press of this kind including two distinct motor 35 means, one of which operates to couple the separable parts and the other of which operates the pressing members for the production of final heavy pressure, together with two hand control means for one or both of said motor means with 40 its consequent safeguarding effect.

Another object of the invention is to provide a press of the kind in which one motor means is utilized both for preliminarily closing the press and for coupling the separable parts, and a second motor means is utilized for producing final 45 heavy pressure for the pressing operation, the press preferably also including safeguarding two hand control means.

A further object of the invention is to provide 50 a press including two fluid pressure motor means, one of which produces preliminary press closing movement or part thereof, and the other of which is arranged to produce final heavy pressure, one of said motor means being also arranged to function as a transmitter of pressure to the other or

as a pump to produce pressure for operating the other, with consequent interconnection and the ability to control both of the motors by one set of control devices.

A further object of the invention is to provide 5 a press of this kind including two fluid pressure motors, one of which first operates as a pump to supply pressure for the other and second, as a motor means to transmit power effect directly to the pressing members.

Another object of my invention is to provide a press of the class described including cooperating 10 pressing members, means for causing pressure therebetween including a fluid actuated motor, operator operated means for controlling a preliminary supply of pressure fluid to the motor, and means responsive to predetermined resistance to movement of the movable pressing member for connecting said motor directly to a final 15 supply of motive fluid.

Another object of my invention is to provide a press of the class described including cooperating 20 pressing members, a motor and motion transmitting mechanism for causing final pressure between said members including separable parts normally ineffective to transmit motion 25 until the press is preliminarily closed, means for preliminarily closing the press and coupling said parts in effective position, and means preventing the machine going into final pressure, even 30 though the press has reached its preliminarily closed position, until after the operator releases a control member for the motor.

Other objects and advantages will be apparent to those skilled in the art and include the 35 novel mechanisms and devices described in the accompanying specification and disclosed in the drawings.

In the drawings, Fig. 1 is a view of a press 40 embodying my invention with the pressing members in open position and with certain of the parts broken away to more clearly disclose the structure; Fig. 2 is a view similar to Fig. 1, with the pressing members in closed position and with certain structural portions in section; Fig. 3 is a 45 diagrammatic layout of a control mechanism for my press; Figs. 4 and 5 illustrate a modification of a portion of the mechanism illustrated in Figs. 1, 2, and 3, in Fig. 4 the parts are in press- 50 open position and in Fig. 5 they are in press- closed position; Fig. 6 is a sectional view along line 6—6 of Fig. 5; while Fig. 7 is a sectional view along the line 1—1 of Fig. 6.

The embodiment of my inventive concept disclosed in Figs. 1 to 3 comprises a stationary press- 55

ing bed member 10 mounted on a suitable frame 11, and a cooperating pressing head member 12 carried by a head lever 13 which is pivotally mounted at 14 on the frame. Mechanism for closing the press comprises a cylinder and piston motor 15 yieldingly mounted on the frame at 16, as will be hereinafter more particularly described, and provided with a piston 17 and a piston rod 18 pivotally connected at 19 to a power lever 20 which in turn is pivotally mounted at 21 on the frame 11. The connection between the power lever and the head lever for moving the latter into final pressing position includes a strut 22 pivotally connected to the head lever at 23 and normally in uncoupled or ineffective position as indicated in Fig. 1. Motion transmitting mechanism connected between the motor 15 and head lever 13 for preliminarily closing the press includes a fluid actuated motor 24 which also 20 actuates a bellcrank 25 which moves strut 22 to coupled or effective position as seen in Fig. 2, when the press is preliminarily closed. These parts will now be described in greater detail.

A lost motion connection is provided between 25 piston 17 and its piston rod 18, and the motion of the piston during the first portion of its stroke is utilized to cause preliminary closing of the press. This lost motion connection comprises a piston rod member 18' which is adapted to telescope within the rod 18 and is slidably secured therein by means of a stud 26 threaded in the rod 18 and extending into a slot 27 in the rod member 18'. A spring 28 biases the piston rod portions 18 and 18' in their extended position. 30 The piston rod 18 is provided with the usual packing gland 29 and the piston 17 is provided with oppositely facing cups 30 so that it may work against a pressure fluid on either face.

The fluid motor 24 has a piston 31 connected 40 by a rod 32 with the head lever at 33. It is desirable that the motor 24 act upon the head 12 with less power than the motor 15. To this end, the cylinder of motor 24 is made of less diameter than the cylinder of motor 15, and the rod 32 is pivoted to the head lever with less of a lever arm than the strut 22. The upper end of the press closing cylinder 31' is provided with a vent 34. The lower end of cylinder 31' is pivotally mounted at 35 on one arm of the bellcrank 25, which in turn is pivotally mounted at 36 on the power lever 20. The other arm of bellcrank 25 carries members 37 and 38 which lie on opposite sides of strut 22 for the purpose of moving the strut about its pivot 23 as the bellcrank oscillates about its pivot 36. The lower end of cylinder 31' is connected by conduit 39 with the lower end of cylinder 17' so that fluid compressed upon movement of piston 17 downwardly in its cylinder will be conducted to the lower face of piston 31. The lower end of cylinder 31' is also in communication with a normally closed exhaust valve 40 operable by its valve stem 41 in a manner hereinafter described. A spring 42 is connected between the rear end of the head lever and bellcrank 25 and normally tends to hold the head in open position and to bias the bellcrank 25 at the counterclockwise limit of its oscillation, as viewed in Figs. 1 and 2. This counterclockwise movement is adjustably limited by a screw 43 which contacts a portion of power lever 20.

Power lever 20 is biased in a counterclockwise direction as viewed in Figs. 1 and 2 by a spring 44 connected to a portion of the frame. This movement is limited by an adjustable screw 45 75 which extends between the frame 11 and a down-

wardly extending projection 46 on the power lever. The rear end of the power lever is bifurcated as shown at 47 to permit the lower end of strut 22 to extend therebelow when the press is in open position, as shown in Fig. 1. A pair of rearwardly extending projections 48 on the rear end of the power lever lie on opposite sides of strut 22 to guide it during its movement. The strut rides against a shoulder 49 on the lever 20 during the latter part of its movement into effective position and when it reaches that position the end of the strut rests upon a hardened bearing block 50 which forms a part of the power lever. A spring-pressed buffer member 51 is secured to the lower end of the strut for the purpose of quietly guiding the strut into its effective position.

Operator operated means is provided for controlling the flow of pressure fluid from a source 52 to motor 15. In the form disclosed this comprises a pair of combined inlet and outlet valve casings 53 and 54 connected in series. Each of these casings encloses a normally closed inlet valve 55, 55' and a normally open exhaust valve 56, 56' mounted on a common stem 57, 57' for 20 operation by a manual 58 and 58'. Conduit 59 connects valve casing 53 with the supply conduit. Conduit 60 connects valve casings 53 and 54, and conduit 61 connects valve casing 54 with valve casing 62 which in turn is connected with the upper end of cylinder 17' by means of conduit 63. Connected with valve casing 53, or mounted separately if desired, is a normally closed pressure release valve 64 in a casing 65 connected by conduit 66 with conduit 63, this release valve 35 being operable by valve stem 67 and manual 68.

The function of the mechanism in casing 62 is to bypass the manuals 58 and 58' and connect the cylinder 17' directly with the source of fluid supply upon the development of a predetermined 40 pressure between the pressing members. The casing contains a normally open inlet valve 69 biased in that direction by spring 70, and a normally closed inlet valve 71 biased in that direction by spring 72. It will be noted that conduit 45 63 enters casing 62 intermediate these two valves, that spring 72 is heavier than spring 70, and that the upper surface of the valve disk of valve 71 presents a greater area than the lower surface thereof, as viewed in Fig. 3. As a result of this 50 structure, pressure supplied through conduit 61 is sufficient to retain valve 71 closed until it is opened by mechanism about to be described. Cylinder 17' is pivotally mounted at 16 on an arm 73, which is pivotally connected at 74 to a bracket 75 which forms part of a base plate connected with the frame. Arm 73 is biased away from the base plate by a spring 76 which is so calculated that it is compressed under a load slightly less than the pressure exerted by the 60 motive fluid in cylinder 17' upon the effective area of the upper end thereof. The movement of arm 73 toward the base plate is limited by a stop member 77. Arm 73 carries a projection 78 which contacts the stem of valve 71 and is adapted to open the valve when spring 76 is compressed.

The operation of the mechanism thus far described is as follows: With the parts in the position of Figs. 1 and 3, the operator arranges the 70 lay of the work upon the bed 10 and actuates the manuals 58 and 58'. It will be noted that this is a well known structure which requires the use of both hands to supply effective pressure fluid through conduit 61, open valve 69 and con- 75

duit 63 to the upper face of piston 17. Piston 17 moves downwardly in its cylinder; meanwhile the pressure in the upper end of the cylinder remains at a low figure as long as the piston moves easily. Air compressed in the lower portion of cylinder 17' by the advancing piston travels through conduit 39 to cylinder 31' where it is effective against the lower face of piston 31 to cause upward travel thereof and a corresponding movement of head 12 toward a preliminarily closed position. When the head reaches safe closed position in contact with the bed (or when the head meets sufficient obstruction anywhere in its downward course, as hereinafter discussed) the parts are so constructed and arranged that piston 17 is somewhat short of contact with the upper end of rod 18. At this time, the pressure against the lower face of piston 17 has built up to substantially line pressure due to the obstruction which prevents further movement of piston 31. Concurrently, the pressure on the upper face of piston 17 has built up to an equal degree and since further movement of piston 17 is prevented by the fluid trapped therebeneath, cylinder 17' will move upwardly sufficient to compress spring 16, whereupon projection 78 opens valve 71 and simultaneously closes valve 69. This establishes the bypass around the manually operated valves in casings 53 and 54 so that the upper portion of cylinder 17' is in direct communication with a source of pressure fluid. However, nothing further will happen unless strut 22 has been moved to its effective position, as shown in Fig. 2, by oscillation of bellcrank 25 in a clockwise direction about its pivot. It will be obvious that when pressure fluid is supplied to cylinder 31', piston 31 moves up as already described, but at the same time, cylinder 31' moves downwardly to oscillate the bellcrank. Member 37 on the bellcrank exerts a yielding pressure tending to move strut 22 counterclockwise as viewed in Figs. 1 and 2, and when the strut snaps into its effective position, as shown in Fig. 2, a shoulder 79 on bellcrank 25 contacts the stem 41, thus opening valve 40. This action alone produces no immediate results (except as hereinafter described) because the exhaust through valve 40 is prevented by a check valve 80, not previously described, which communicates by conduit 81 with conduit 61 and valve casing 54. If the operator is maintaining manual 58' in its operative position so as to hold exhaust valve 56' closed, at the time strut 22 reaches effective position and valve 40 is operated, nothing will happen because the pressure on opposite sides of valve 80 will be substantially equal and spring 82 will serve to maintain the valve closed. If, however, manual 58' is released, fluid in conduit 81 will be exhausted through valve 56', check valve 80 will open, pressure will be relieved in the lower portion of cylinder 31' and in conduit 39, and on the lower face of piston 17. Piston 17 will then continue its downward travel, thus contacting piston rod 18 so as to apply power to lever 20, strut 22 and head lever 13, so as to close the press under final pressure. When the pressing operation is completed, the operator will actuate manual 68 which will permit fluid to exhaust from above piston 17 through conduit 66 and valve 64. Springs 42, 44 and 76 will then return the parts to press open position.

The parts are so designed that spring 76 is compressed and strut 22 reaches effective position before piston 17 contacts rod 18. However, 75 a certain amount of adjustment is necessary in

the field due to compression of padding on the pressing members, wear of the parts, etc., so that further adjustment of this point of contact is provided by the member 45 which limits the position of the upper end of rod 18, as biased by spring 44, when the press is in open position.

An examination of the drawings will show that if head 12 is held at any point with sufficient force to build up substantially line pressure against piston 31, spring 76 will be compressed and valve 71 will be operated. But it is impossible for piston 17 to contact rod 18 and deliver heavy pressure to head 12 until the press is safely closed, whereupon valve 40 is actuated to relieve the trapped fluid under piston 17 and to permit that piston to complete its stroke.

In the modification shown in Figs. 4 to 7 I utilize the same press structure and control mechanism already described, modifying only the connection between the power lever and the head lever and the position of the auxiliary motor. This modified structure comprises a strut 22a which is adapted to extend downward through the bifurcated end 47 of power lever 20 when the press is in open position as shown in Fig. 4. The motor 24a performs a function similar to the motor 24 already described, that is to say, the piston rod 32a is connected by a bracket 83 with the strut 22a, and the cylinder 31'a is pivotally connected at 84 with one arm of a bellcrank member 85, the other arm of which carries a bearing block 86 which is adapted upon proper bellcrank oscillation to move between the lower end of strut 22a and the bifurcated end 47 of the power lever to thereby form an effective motion transmitting mechanism between the power lever and the head lever. Bellcrank 85 is pivotally mounted on pins 87 which are reciprocatingly mounted by bars 88 in a bracket 89 which is pivotally mounted to swing about the point 21. Bars 88 are yieldingly held in bracket 89 so as to permit a slight movement of pin 87 and bellcrank 85 when pressure is applied by power lever 20 through the strut 22a. The cylinder of motor 24a is connected by a conduit 39a with the main power cylinder in the manner described in Figs. 1 to 3. The cylinder of motor 24a also communicates by conduit 90 with a normally closed exhaust valve 40a in all respects similar to valve 40 and operable by its stem 41a which contacts with a portion of bellcrank 85 when the parts reach effective position to accomplish the same purpose as similar mechanism described in Figs. 1 to 3.

It is thought unnecessary to describe the operation of the modification of Figs. 4 to 7 in detail as it is in all respects analogous to that already described. The first portion of the power stroke of the main piston forces fluid under pressure into motor 24a, causing the piston thereof to move upward which moves the head lever toward closed position, and simultaneously causing the cylinder thereof to move downward which moves pressure block 86 into effective position as soon as strut 22a permits such movement. With the parts in the position of Fig. 5, valve 40a is opened which, when check valve 80 opens upon release of a manual as already described, relieves the trapped fluid beneath the main piston, and this permits sufficient movement of the main piston to actuate the power lever so as to act upon strut 22a to close the press under final pressure.

What I claim is:

1. A pressing machine comprising cooperat-

ing relatively movable pressing members, a fluid actuated cylinder and piston motor for producing such movement, motion transmitting mechanism effective during the latter part of the piston stroke for applying final pressure between said members and including separable parts effective to transmit motion only when the pressing members are in close proximity, power transmitting mechanism operatively connected with said piston for producing relative motion between said pressing members and effective during the first part of the piston stroke to move said members to close proximity and to couple said parts in effective position, and operator controlled means for actuating said motor.

2. A pressing machine comprising cooperating relatively movable pressing members, a cylinder and piston motor for producing said relative movement, motion transmitting mechanism effective during the latter part of the piston stroke for applying final pressure between said members and including separable parts effective to transmit motion only when the pressing members are in close proximity, power transmitting mechanism operatively connected with said piston during the first part of its stroke for relatively moving the members to close proximity and for moving said parts to effective position, operator controlled means for actuating said motor, and means for preventing the latter portion of said piston stroke until said parts are in effective position.

3. A pressing machine comprising a pair of cooperating relatively movable pressing members, a cylinder and piston motor for causing said relative movement, the piston of said motor having power transmitting mechanism operatively connected therewith for producing relative movement between said pressing members and effective during the first part of said piston stroke to preliminarily close the press, motion transmitting mechanism having an operative connection with said piston for causing relative movement of said pressing members into final pressure position, there being a lost motion connection between said piston and said last named mechanism, said last-named mechanism having parts ineffective to transmit motion in press open position, and means operated by said power transmitting mechanism for making said parts effective to transmit motion.

4. In a press of the class described, cooperating relatively movable pressing members and operating mechanism therefor comprising a cylinder and piston motor having operative connections with one of said members for causing final pressure between said members, a second cylinder and piston motor constructed and arranged to cause relative approach between said members with lower power than said first motor, means for compressing a fluid by operation of said first motor, and means for supplying said compressed fluid to said second motor.

5. In a press of the class described, cooperating relatively movable pressing members and means for causing pressure therebetween including a fluid actuated motor, operator operated means for controlling the supply of pressure fluid to the motor, said motor being arranged for a shifting movement responsive to predetermined resistance to relative movement of said pressing members, and means actuated by said motor shifting movement for connecting said motor directly to a source of motive fluid.

75 6. In a press of the class described, cooperat-

ing relatively movable pressing members, a fluid actuated cylinder and piston motor, there being a lost motion connection between the piston and piston rod of said motor, motion transmitting mechanism between said rod and one of said pressing members for applying final pressure thereto, a second fluid operated motor having operative connections for preliminarily closing said press, and means for supplying to said second motor fluid compressed by movement of said piston in said first motor while taking up said lost motion connection.

7. A pressing machine comprising cooperating relatively movable pressing members, a fluid actuated cylinder and piston motor having a lost motion connection between its piston and piston rod, motion transmitting mechanism between said rod and one of said pressing members for applying final pressure thereto including separable parts adapted to be coupled and uncoupled, means normally tending to uncouple said parts, a second fluid actuated motor for preliminarily closing said press and coupling said parts, means for supplying to said second motor fluid compressed by movement of said piston in said first motor while taking up said lost motion connection, said compressed fluid being trapped in said motors when said press is preliminarily closed to arrest the movement of said piston of said first motor short of effective contact with its piston rod, and means for releasing said trapped fluid when said parts are coupled.

8. A pressing machine comprising cooperating relatively movable pressing members, a cylinder and piston motor for producing said relative movement, motion transmitting mechanism effective during the latter part of the piston stroke for applying final pressure between said members and including separable parts effective to transmit motion only when the pressing members are in close proximity, power transmitting mechanism operatively connected with said piston during the first part of its stroke for relatively moving the members to close proximity and for moving said parts to effective position, operator controlled means for actuating said motor, and means for normally preventing the latter portion of said piston stroke and including a device actuated to piston actuating position by said parts upon reaching effective position and a manual controlled by the operator, whereby upon said parts reaching effective position and upon operation of said manual final pressure is produced.

9. A pressing machine comprising coacting relatively movable pressing members, fluid actuated power means for relatively moving said members to close the press, said power means including a cylinder and piston motor, said piston having an operative connection with one of said pressing members, said cylinder having a support providing a lost motion connection, manually operated means for supplying motive fluid to the working face of said piston, means actuated by the taking up of said lost motion connection for supplying motive fluid to the working face of said piston independently of said manually operated means, said power means being arranged to trap fluid in said motor in advance of said piston whereby said piston is held and said cylinder takes up said lost motion connection, and means actuated upon release of said manually operated means for exhausting said trapped fluid.

10. A pressing machine comprising a frame, a pressing bed on said frame, a head lever piv-

totally mounted on said frame intermediate its ends, a pressing head on one end of said lever and movable thereby into and out of engagement with said bed, a pry bar pivotally mounted on said frame, a motor for actuating said bar, a pressure strut pivotally carried by the other end of said head lever and movable into and out of power transmitting relation with said pry bar, a pivoted bell-crank having one arm operatively connected with said strut, a second motor having cylinder and piston elements, one of said elements being connected with said head lever to move it in press-closing direction, the other of said elements being connected with the other arm of said bell-crank for moving the same to actuate said strut into power transmitting position, and means for operating said motors.

11. A pressing machine comprising a frame, a pressing bed on said frame, a head lever pivotally mounted on said frame intermediate its ends, a pressing head on one end of said lever and movable thereby into and out of engagement with said bed, a pry bar pivotally mounted on said frame, a motor for actuating said bar, a pressure strut pivotally carried by the other end of said head lever and movable into and out of power transmitting relation with said pry bar, the end of said strut in power transmitting position lying over an opening in said bar, a pivoted bell-crank having one arm arranged to position a bridging abutment over said opening, a second motor having cylinder and piston elements, one of said elements being connected with said head lever to move it in press-closing direction, the other of said elements being connected with the other arm of said bell-crank for moving the same to actuate said abutment into bridging position, and means for operating said motors.

12. A pressing machine comprising coacting relatively movable pressing members, fluid actuated power means for relatively moving said members to close the press, said power means including a fluid motor having cylinder and piston elements, one of said elements having an operative connection with one of said pressing members, the other of said elements having a support providing a lost motion connection, said power means being arranged to trap fluid in said motor in advance of the movable element thereof whereby said movable element is held and said other element takes up said lost motion connection, manually operated means for supplying motive fluid to said motor, means actuated by the taking up of said lost motion connection for supplying motive fluid to said motor independently of said manually operated means, and means for releasing said trapped fluid.

13. A pressing machine comprising cooperating pressing members relatively movable to preliminary closed position and to final pressing position, power means for relatively moving said members including fluid compressing means and a motor for causing relative approach movement between said members to preliminary closed position, two-hand control means for said compressing means, means for supplying said compressed fluid to the preliminary closing motor, and means for causing further actuation of said power means to cause final pressure between said pressing members.

14. A pressing machine comprising cooperating relatively movable pressing members, a motor and connected power transmitting mechanism for relatively moving said members to apply final pressure between them, said mechanism includ-

ing separable parts adapted to be coupled when said pressing members are in safe-closed position, means normally tending to uncouple said parts, a motor for coupling said parts, two-hand control means for said coupling motor, said final pressure motor having an energizing circuit and a control member therefor, and actuating means for said control member including a part of said two-hand control means and a part operated by placing of said pressing members in safe-closed position.

15. A pressing machine comprising cooperating pressing members relatively movable to preliminarily closed position and to final pressing position, a motor and connected power transmitting mechanism for relatively moving said members to apply final pressure between them, said mechanism including separable parts adapted to be coupled and uncoupled, one of said parts being carried by a movable pressing member to coupling position only when the press is in preliminarily closed position, means normally tending to uncouple said parts, a motor for coupling said parts, two-hand control means for said coupling motor, said final pressure motor having an energizing circuit and a control member therefor, and actuating means for said control member including a part operated by placing said members in preliminarily closed position.

16. A pressing machine comprising cooperating pressing members relatively movable to preliminarily closed position and to final pressing position, a motor and connected power transmitting mechanism for relatively moving said members to apply final pressure between them, said mechanism including separable parts adapted to be coupled and uncoupled, means normally tending to uncouple said parts, motor means for preliminarily closing said pressing members and for coupling said parts, two-hand control means for said coupling motor, said final pressure motor having an energizing circuit and a control member therefor, and actuating means for said control member including a part of said two-hand control means and a part operated by movement of said separable parts to coupled position.

17. A pressing machine comprising cooperating pressing members relatively movable to preliminarily closed position and to final pressing position, a motor and connected power transmitting mechanism for relatively moving said members to apply final pressure between them, said mechanism including separable parts adapted to be coupled and uncoupled, one of said parts being movable to coupling position only when the press is in preliminarily closed position, means normally tending to uncouple said parts, a motor for coupling said parts, two-hand control means for said coupling motor, said final pressure motor having an energizing circuit and a control member therefor, and actuating means for said control member including a part of said two-hand control means and a part controlled by movement of said parts to coupled position.

18. In a press of the class described, cooperating relatively movable pressing members, fluid actuated power means for closing said press, operator controlled means for supplying pressure fluid to said power means, means for establishing a direct connection between a source of fluid supply and said power means including a shiftable part normally in fluid cut-off position, means for trapping fluid by press closing operation of said power means to retard press closing opera-

75

tion thereof, means for shifting said shiftable part when said trapped fluid attains a predetermined pressure, and means for releasing said trapped fluid.

5 19. In a press of the class described, cooperating relatively movable pressing members and means for causing pressure therebetween including a fluid actuated motor, operator operated means for controlling the supply of pressure fluid 10 to the motor, means for trapping fluid by press closing operation of said power means so as to retard said closing operation, mechanism controlled by the pressure of said trapped fluid for bypassing the operator operated means and for 15 connecting said motor directly to a source of motive fluid, and means for releasing said trapped fluid.

20. A pressing machine comprising cooperating pressing members relatively movable to preliminary closed position and to final pressing position, a cylinder and piston motor, means operated by the first portion of said motor stroke for causing movement of said members into preliminary closed position, means operated by the 25 latter portion of said motor stroke for causing movement of said members into final closed position, said motor being constructed and arranged to compress fluid ahead of said moving piston by the said first portion of said motor stroke to 30 prevent said latter portion of said stroke, and

means for releasing said compressed fluid including a part actuated by movement of said members into preliminary closed position, whereby said motor may then continue through the latter portion of its stroke.

21. A pressing machine comprising cooperating 5 pressing members relatively movable to preliminary closed position and to final pressing position, a cylinder and piston motor, means operated by the first portion of said motor stroke for causing movement of said members into preliminary closed position, means operated by the latter portion of said motor stroke for causing movement of said members into final closed position, means controlled by said first portion of said motor stroke for retarding motor operation at the end of said first portion of said stroke, and means for releasing said retarding means including a part actuated by movement of said members into preliminary closed position, whereby said motor may then continue through the latter portion of its stroke unretarded.

22. A pressing machine as in claim 21 including a two-hand safety controlled motive fluid supply for said motor, and a fluid supply for said motor independent of said first-named supply, and means for establishing said latter supply by operation of said motor through the first portion of its stroke.

JOSEPH P. DALY. 30
